Primary Examiner — Eric L Goodman

Assistant Examiner — Sarah L Smith

(57) **CLAIM**

The ornamental design for a working light, as shown and described.

DESCRIPTION

FIG. 1 is a front, left side and top perspective view of a working light showing my new design;

FIG. 2 is a rear, left side and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, showing a open state; and,

FIG. 10 is an enlarged view of the working light taken from the circled portion in FIG. 1.

The broken lines showing of the enlargement indicia in FIGS. 1 and 10 is shown for the purpose of illustrating the bounds of the enlargement and forms no part of the claimed design.

The broken lines shown illustrate portions of the working light in FIGS. 3, 4, and 6 that form no part of the claimed design.

1 Claim, 10 Drawing Sheets(56)
